UNITED STATES PATENT OFFICE.

LE ROY FLETCHER SNAPP, OF BROOKLYN, NEW YORK.

SWIMMING APPLIANCE.

Application filed May 17, 1923. Serial No. 639,535.

To all whom it may concern:

Be it known that I, LE ROY FLETCHER SNAPP, a citizen of the United States, and resident of Brooklyn, county of Kings, State of New York, have invented an Improvement in Swimming Appliances, of which the following description, in connection with the accompanying drawing, is a specification, like characters on the drawing representing like parts.

This invention relates to a swimming appliance of the type having wings which fold and spread in their own planes when the appliance is in use.

The swimming appliance is designed to be held on the hand of the swimmer and when the hand is being pushed forward as when the swimmer is using the so-called "breast stroke" or "claw stroke" the wings automatically fold into such a position that they offer little resistance to the water but when the hand is being pulled backward the wings automatically spread to give an enlarged surface for bearing against the water so that great force may be exerted to push the body of the swimmer forward.

A special type of reversible hand grip or guard has been designed for use with the appliance in order to permit the appliance being used when the swimmer is swimming with the "overhand" stroke in which the hand enters the water in a manner different from the breast stroke. In using the overhand stroke the forward part of the hand enters the water first and since it is desirable that the wings of the appliance spread at this time and close when the hand is withdrawn from the water, the action of the appliance must be reversed. By the use of the reversible hand grip or guard the position of the appliance with reference to the hand of the swimmer may be easily reversed so that the appliance may be adapted for use with any stroke.

The objects and features of the invention will more fully appear from the following description and the accompanying drawings and will be particularly pointed out in the claims.

The drawings illustrate in perspective, elevation, and section a preferred form of construction of a swimming appliance and embody the broad principles of the invention.

In the drawings:

Fig. 1 is a perspective of the appliance on

the hand of the swimmer with the wings spread;

Fig. 2 is a bottom view of the appliance with the wings spread;

Fig. 3 is a bottom view of the appliance with the wings folded;

Fig. 4 is a section through the guard for the hand and the body of the appliance;

Fig. 5 is a section on line 5—5, Fig. 3;

Fig. 6 is a section on line 6—6, Fig. 3;

Fig. 7 is a section on line 7—7, Fig. 3;

Fig. 8 is a partial bottom view of a modified form of the appliance with a wing spread;

Fig. 9 is a partial view of the modified form of the appliance with a wing partially folded.

As illustrated herein the swimming appliance which constitutes the subject matter of the present invention comprises a rigid body 1 and a guard 2 fastened to the body for retaining the body on the hand of the swimmer. Wings 3 and 4 extend on either side of the body in order to give an enlarged surface for bearing against the water when the swimmer is making a backward stroke to force his body forward through the water. Links 5, 6, 7, and 8 connect the wings to the body in such a manner that when the hand of the swimmer is being pushed forward after the completion of one stroke and in preparation for taking another stroke, the wings are permitted to fold beneath the body in order to offer very little resistance to the water in their movement therethrough. The wings and links are so arranged that the wings are extensible on either side of the body in planes parallel to the plane of the body and the links are also of such a shape that they present edges of very small surfaces to the water when the hand of the swimmer is being pushed forward to take a stroke.

The wings may be of any suitable shape. I have shown the wings as being just so large that the inner edge 9 of each wing lies under the outer edge 10 of the body in order that a plane surface having no openings therethrough will be presented when the wings are spread. In order to insure that the links and wings will always fold into the proper position and not jam, one link of each pair of links which connect the wings to the body has a portion always engaging a similar portion on the corresponding link of the opposite pair to guide the links and

wings into the proper folded position. As shown on the drawing the links 5 and 6 constitute one pair fastening the wing 3 to the body and the links 7 and 8 constitute a second pair fastening the wing 4 to the body. The link 6 has a portion 11 always engaging a similar portion 12 on the corresponding link 8 of the opposite pair and it will be obvious that when the wings are folded the portion 11 slides in between the portion 12 and the body 1 every time the wings are folded. As shown in Fig. 2 the wings are extended to their farthest position and the inner end of the portion 11 of the link 6 is under the corresponding portion 12 of the link 8. I prefer to make the links of the form shown in the drawings in order that the links may assist in closing any spaces between the wings and the body.

The body, wings, and links are pivotally connected and spaced from one another where necessary in order that they may fold properly. As illustrated herein rivets 13 are used to connect the body, wings, and links, and washers 14 surrounding the rivets are used as spacing elements. The inner edge 15 of the outer wing 3 is turned up to guide the wing 4 into the proper folded position. It is obviously necessary that the rivets be tight enough to keep the wings and links in their proper planes when extended, but yet loose enough so that they will not hinder the free movement of the parts of the appliance.

Means are provided to automatically open and close the links and wings when the appliance is being used and for limiting the spreading and folding movement of the wings. Each wing has a turned down portion at its front and rear end, thus wing 4 has a turned down portion 16 on its front end and a turned down portion 17 on its rear end. Wing 3 has corresponding portions 18 and 19. The front ends 20 and 21 of portions 16 and 18 respectively are bent inwardly. It is readily seen that when the device is being pushed forward through the water, the water bears against the portions 16 and 18 and the bent in ends 20 and 21 on the forward end of the wing and the portions 17 and 19 on the rear end of the wing to automatically close the wings but when the device is being pulled backwardly through the water, as when the swimmer is taking a propelling stroke, the pressure of the water against the portions 17 and 19 and the portions 16 and 18 and the front ends 20 and 21 will automatically spread the wings to open the device and give an enlarged surface for bearing against the water.

The rear end of the body is turned down giving a projection 22 from the body into the planes of the wings to engage the wings and prevent the wings moving past the fold-

ed position. The manner in which the wings or the portions 17 and 19 thereof engage the projections 22 is clearly shown in Figs. 3 and 7. The forward end 23 of the body is turned down as shown and the forward links 5 and 7 have portions 24 and 25 which abut against the turned down end to limit the spreading movement of the links.

The guard for retaining the device on the hand of the swimmer may be of any suitable shape but is preferably of the design shown in the drawings and is removably retained on the body. The guard is shaped to fit the back of the hand and has projections 26, 27, 28, and 29 thereon for engagement under retainers 30, 31, 32, and 33 on the body of the appliance. The retainers may conveniently be struck up portions of the body and the guard is resilient to force the projections under the retainers to hold the guard on the body. By using this construction it is obvious that the guard may be easily removed from the body of the appliance and reversed if a back-hand or other stroke is to be used by the swimmer which necessitates the appliance spreading on the forward stroke instead of the rearward stroke of the swimming movement.

A flexible pad 34 is resiliently mounted within the guard to fit the palm of the hand and press the hand between the guard and the pad in order to retain the hand within the guard. Such pad may conveniently be a turned up end of the guard. In order to give greater pressure on the pad 34 the other end of the guard 35 is turned up beneath the pad 34 so that when the hand is forced in between the top 36 of the guard and the pad, the pad 34 is pressed downwardly against the end 35 and thus the resiliency of both ends 34 and 35 are brought into use to securely but removably hold the hand of the swimmer in the guard.

The projection 29 may conveniently be extended at 37 to form a thumb holder for holding the thumb adjacent the guard in the position shown in Fig. 1. This projection also serves as a point against which the thumb of the swimmer may be brought if it is desired to quickly remove the appliance from the hand. Hence by simply doubling the thumb and pushing against the end 37, the hand may be slipped within the guard and the appliance removed.

The modified form of appliance shown in Figs. 8 and 9 is the same in all essential characteristics and operates in substantially the same manner as the form of appliance shown in Figs. 1 to 7 inclusive. In the modified form of appliance the forward and rear links and the wings have been modified slightly in order to provide a means for limiting the spreading movement of the wings and links and at the same time provide additional means to automatically

spread and fold the wings. Links 38 and 39 correspond to links 5 and 6 respectively and the wing 40 to the wing 3 shown on Fig. 2.

5 Instead of having the front end 23 of the body turned down to form a stop for the link 5 and the front end 21 of the portion 18 bent inwardly, all as shown in Figs. 2 and 3, the front end 41 of link 38 has been 10 turned down to engage a portion 43 on the wing 40, thereby combining the desirable features of both of the front ends 21 and 23 by providing a stop for limiting the spreading movement of the wings and a means to 15 automatically spread and fold the wings, and at the same time form a structure which offers little resistance to the water when moved forwardly therethrough. Thus instead of having the means for spreading and 20 folding the wings entirely on the wings, part has been left on the wings and part has been put on the links. The end 41 is undercut to form a groove through which the front end 42 of the wing 40 may pass 25 when spreading or folding. It is obvious from the position of the turned down end 41 shown in Figs. 8 and 9 that when the appliance is in position with the wings spread said end 41 assists in holding the wings in 30 spread position during the back, or swimming, stroke of the swimmer, and that during the forward stroke the water bears against the end 41 to assist in folding the appliance.

35 Although particular and preferred forms of construction have been described, the invention is to be construed as broadly as the claims, taken in conjunction with the prior art, may allow.

40 Having thus described the invention, what is claimed as new, and desired to be secured by Letters Patent is:

1. A swimming appliance comprising a rigid body, wings extensible on either side of the body in planes parallel to the plane of the body, and links connecting the wings and body to permit the wings folding under the body in planes parallel to the plane of the body.

45 2. A swimming appliance comprising a rigid body, wings extensible on each side of the body in planes parallel to the plane of the body, and pairs of similar links connecting each wing to the body to permit the wings folding under the body, one link of each pair having a portion always engaging a similar portion on the corresponding link on the opposite pair to guide the links and wings into the proper folded position thereby preventing jamming of the parts when folding.

50 3. A swimming appliance comprising a

body, wings folding in the plane of the body, and a reversible guard to retain the appliance on the hand of the swimmer, 65 whereby the appliance is rendered reversible in action and adjustable to the various strokes of the swimmer.

4. A swimming appliance comprising a rigid body, wings extensible on either side 70 of the body in planes parallel to the plane of the body, links connecting the wings and body to permit the wings folding under the body and to retain the inner edges of the wings under the body when the wings are 75 in extending position and a removable reversible means to retain the appliance on the hand of the swimmer.

5. A swimming appliance having a rigid body and wings extensible on either side 80 thereof, means to retain the appliance on the hand of the swimmer comprising a guard to fit the back of the hand fastened to the body, and a flexible pad to fit the palm of the hand resiliently mounted to press the hand between the guard and the 85 pad.

6. A swimming appliance having a rigid body and wings extensible on either side thereof, means to retain the appliance on the hand of the swimmer comprising a guard to fit the back of the hand removably fastened to the body, a flexible pad to fit the palm of the hand resiliently mounted to press the hand between the guard and the 90 pad, and a thumb holder for holding the 95 thumb adjacent the guard.

7. In a swimming appliance having a rigid body with retainers thereon and wings extensible on either side of the body, means 100 to retain the appliance on the hand of the swimmer comprising a resilient guard to fit the back of the hand, a flexible pad to fit the palm of the hand resiliently mounted to press the hand between the guard and the pad, and projections on the guard for engagement under the retainers and held under the retainers by the resiliency of the guard, one of the projections being extended to form a thumb holder for holding 105 the thumb adjacent the guard.

8. A swimming appliance comprising a rigid body, wings extensible on either side of the body in planes parallel to the plane of the body, links connecting the wings and body to permit the wings folding under the body in planes parallel to the plane of the body, and a projection from the body into the planes of the wings to engage the wings and prevent the wings moving past the 110 folded position.

115 In testimony whereof, I have signed my name to this specification.

LE ROY FLETCHER SNAPP.
